US00D629906S

(12) **United States Design Patent**
Hickey et al.

(10) **Patent No.:** **US D629,906 S**
(45) **Date of Patent:** **** Dec. 28, 2010**

(54) **INTERFACE FOR DIALYSIS MACHINE**

(75) Inventors: **Katherine M. Hickey**, Manchester, NH (US); **David W. McGill**, Bedford, NH (US); **Simon C. Helmore**, Manchester, NH (US); **James D. Dale**, Nashua, NH (US); **Jacob W. Scarpaci**, Manchester, NH (US)

(73) Assignee: **DEKA Products Limited Partnership**, Manchester, NH (US)

(**) Term: **14 Years**

(21) Appl. No.: **29/331,313**

(22) Filed: **Jan. 23, 2009**

(51) **LOC (9) Cl.** **24-01**

(52) **U.S. Cl.** **D24/169**

(58) **Field of Classification Search** D24/169, D24/186, 138; D10/81; 210/252, 253, 321.65, 210/321.75, 645, 646; 435/286.5, 297.1, 435/297.2; 604/28, 29, 65, 131; D13/162, D13/164, 184

(57) **CLAIM**

The ornamental design for an interface for dialysis machine, as shown and described.

DESCRIPTION

FIG. 1 is a right perspective view of the interface for dialysis machine;

FIG. 2 is a front side view thereof;

FIG. 3 is a left side view thereof;

FIG. 4 is a right side view thereof; and,

FIG. 5 is a top side view thereof.

The broken lines in the drawing views are included for the purpose of illustrating portions of the dialysis machine that form no part of the claimed design.

1 Claim, 5 Drawing Sheets
